UNITED STATES PATENT OFFICE

JOHN W. COSGROVE, OF MEDFORD, MASSACHUSETTS, ASSIGNOR TO UNITED SHOE MACHINERY CORPORATION, OF PATERSON, NEW JERSEY, A CORPORATION OF NEW JERSEY

CEMENTING MACHINE

Application filed December 10, 1926. Serial No. 153,970.

This invention relates to cementing machines and is illustrated in its application to a machine for cementing shoe parts to which a French binding strip has been applied. It will be understood, however, that the invention may be applied to machines for other kinds of work and the general object of the invention is to provide an improved cementing machine capable of handling work efficiently and with a minimum of skill upon the part of the operator.

Cementing machines have a wide application in applying a coating to various forms of shoe parts, but the type of machine under consideration is designed particularly for the application of a narrow stripe of cement adjacent to the edges of such parts. Machines for this purpose are commonly provided with co-operating superposed rolls either one or both of which are arranged to apply cement, and the arrangement is generally such that the rolls may be separated to allow the introduction of pieces of work therebetween, operator-controlled means being provided to govern the separation and approach of the rolls. In the illustrated machine, in accordance with an important feature of the invention, the shaft of the upper roll is carried in a bracket pivotally attached to the frame of the machine at a point remote from the rolls, a spring being provided to hold up the bracket so that the rolls are normally separated, and an operator-controlled lever is arranged to bear against this bracket to bring the rolls into contacting relation with the work. In order that it may not be necessary for the operator to release the treadle to allow momentary abnormal separation of the rolls as, for example, when a thickened place in the work, such as would be caused by a seam, passes between the rolls, a spring is interposed between the lever and the roll-carrying bracket.

The lower roll of the illustrated machine is supplied with cement from a trough, shaped like an outstretched cylindrical arm, on the frame of the machine and the roll dips in the cement and projects through an opening at the upper side of said trough. To control the quantity of cement taken up by

the lower roll, and in accordance with other features of the invention, a compact and readily adjustable doctor has been mounted upon the trough so that one edge of the doctor co-operates with the upgoing side of the lower roll. In the illustrated construction the trough is provided with a curved outer surface adjacent to the upgoing side of the roll, and the doctor comprises a curved plate closely fitting over this surface and having its upper edge arranged to control the amount of cement taken up by the roll. The adjustment of this doctor plate is facilitated by mounting it upon an arm pivoted about a point eccentric to the center of the roll.

For French binding, strips of material usually of fabric are attached, as by stitching, to the edge of a vamp, quarter, or other shoe part, in flat contact therewith. With the work in this condition, cement may be applied to either one or both of the external surfaces of the strip and shoe part, prior to the time when the strip is folded over the edge and stuck down upon the inside of the shoe part, thereby to conceal the edge of the leather of said part. It will be understood that the proper handling of work to which a French binding strip has been attached requires that the attached strip shall lie flat upon the work when it is introduced between the rolls of the cementing machine. Accordingly, the introduction of work to the rolls is facilitated in the illustrated machine by the provision, in accordance with still other features of the invention, of a forked guide adjacent to the intake of the rolls having a flared entrance provided by an upturned end upon the upper arm of the fork and a depending apron secured to the lower arm of the fork. The arrangement is such that the work cannot be fed through the rolls in a straight line but the upper arm of the fork must drag over the fabric strip to smooth it out.

These and other features of the invention will now be set forth in detail with reference to the accompanying drawings, in which

Fig. 1 is a front elevation of the machine;
Fig. 2 is a perspective view with parts

broken away, showing the cementing rolls and associated parts;

5 Fig. 3 is a fragmentary perspective view of the rolls from the front corner of the machine;

Fig. 4 is an end elevation of the machine;

Fig. 5 is a fragmentary end view, on a larger scale, broken away to show a section through the rolls and the gage; and

10 Fig. 6 is a perspective view of a small section of a shoe part to which a binding strip has been stitched, showing the binding strip in its original position and in its final folded position.

15 The machine herein illustrated is a double cementer arranged to supply cement to both a lower applying roll 10 and an upper applying roll 12, but it will be understood that one or the other of these rolls may be used

20 merely as a work-supporting or pressing roll while cement is supplied to the co-operating roll. The lower roll 10 dips in a barrel-shaped trough 14 constructed as an out-stretched arm rigidly attached to a base 16

25 and supplied barometrically with cement from an inverted receptacle 18 detachably secured to a lateral extension 20 of said trough. This arrangement of an outwardly extending barrel-shaped trough facilitates the use

30 of the machine for parts, such as closed vamps, to which it is desired to apply cement, for example around the inner edge of the vamp. A pivoted cover 24 is provided upon the lower side of the extension 20, which is

35 detachably held in place by means of a wing nut 26 so that the trough may be drained and cleaned of cement when desired. It will be understood that bearings are provided within the trough for a shaft 30 upon which the

40 lower roll 10 is mounted, this shaft being extended through the frame of the machine to support fast and loose pulleys 32 and 34.

A belt shifter 36 is slidably mounted upon a square rod 38 bolted to a bracket 40 secured

45 on the base 16. This belt shifter comprises a curved fork 42 of usual type, a finger piece 44 and a latch 45 actuated by means of a spring 46 to hold the shifter in either of its operative positions.

50 If cement is to be applied by the lower roll 10 alone, then it is essential that the upper roll 12 be kept clean. Accordingly, the machine is arranged so that the rolls are normally separated by a spring 60 to be later described.

55 To this end, the upper roll 12 is mounted upon a shaft 50 journaled in a long bracket 52 pivotally attached at 54 to the frame of the machine so that the upper roll 12 may be moved toward and away from the lower roll 10.

60 Loosely meshing driving gears 56 and 58 are provided upon the shafts 50 and 30, respectively. It will be noted that the pivotal point of the bracket 52 is remote from the rolls and is adjacent to these gears so that the slight

65 movement of the separation and approach of

the upper roll 12 does not disturb the cooperation of the gears. A spring 60, supported in a recess formed in a lug 61 (Fig. 2) on the frame and interposed between that lug and a lug 63 on the bracket arm 52, is arranged to hold the rolls normally separated. The tension of the spring 60 may be adjusted by a bolt 65. This arrangement is indeed desirable even when the machine is used as a double cementer with both rolls used as applying rolls because it has been found that there is a tendency then, in case the rolls are allowed to remain in contact with one another, without feeding work to the machine, for the upper roll to take cement from the lower roll and carry it to the upper reservoir 90 until the latter is filled to overflowing.

70 In order that the rolls may be brought into co-operative relation with the opposite sides of a piece of work, operator-controlled means, such as a lever 62, is provided for depressing the roll-carrying bracket 52 against the tension of the spring 60. This lever is pivotally mounted between upstanding fingers 64 (Fig. 1) and 66 (Fig. 2) which are also arranged

75 to guide the vertical movements of the outer end of the bracket arm 52. The lever 62 is angular in shape, as viewed from above, and is connected at its outer end to a treadle rod 68, which is guided in a lug 70 on the rear side of the frame of the machine and is provided with stop collars 72 and 74, to limit the downward and upward movements of the rod, respectively.

80 A spring 76 encircling the treadle rod and bearing at one end under the collar 74 and resting on a washer 78, assists the spring 60 in counterbalancing the weight of the parts. Thus the rolls are held normally separated and, as a piece of work is

85 introduced between them, are brought into co-operative relation to the work by the depression of the treadle rod 68. Engagement between the angular lever 62 to which this treadle rod is connected and the pivoted bracket 52 carrying the upper roll 12 and shaft 50 is provided by means of a plunger 80 resiliently projected by a spring 82 (Fig. 1) from said lever 62 a slight amount determined by the nuts 84 secured to the other end

90 of the plunger. Thus the two rolls may be held resiliently in engagement with opposite sides of a piece of work and allowed momentarily to separate the passage of a thickened portion of the work, such as would be caused by a seam, for example, without harm thereto and without requiring further attention from the operator. It will be understood that the approach of the rolls is adjustably determined by means of a stop 86 engaging the

95 frame of the machine.

ranged for actuation by a pivoted lever 96 having a slot for engagement with a pin 98 on said valve 94. The extent of the opening movement of the valve may be determined by a screw stop 100 mounted in said lever and arranged to engage one of a pair of forked lugs 102 at the bottom of the reservoir. These lugs are arranged to be engaged by wing nuts 104 mounted upon bolts pivoted in lateral extensions 106 upon the bracket arm 52. Thus by closing the valve 94 the flow of cement may be prevented and the wing nuts 104 loosened to allow the removal of the upper reservoir 90. The flow of cement to the upper roll 12 is controlled by means of a member 110 adjustably mounted and held in position upon a dovetailed slide 112 by means of a bolt 114. This arrangement is substantially identical with that illustrated and 10 claimed in a pending application of J. W. Cosgrove Serial No. 686,822, filed Jan. 17, 1924, for cementing machines. In common with that arrangement a scraper is provided upon the adjustable member 110 and the position 15 of this scraper with respect to the roll 12 is determined by means of a screw 116 arranged to move the dovetailed slide 112 and its attached parts from front to back, as the machine is viewed in Fig. 1.

20 The mechanism for controlling the flow of cement to the upper roll has already been described, and in order that the amount of cement carried up to the work by the lower roll, as it dips in the cement carried in the trough 14, may be controlled, I have provided a doctor in the form of a curved plate 120, the upper edge 122 of which is reduced in thickness and adapted to be brought into co-operative relation with the upgoing part of the roll 10 to control the thickness of the coating of cement carried thereby. A portion 124 of the surface of the outside of the trough 14 is curved and the doctor 120 is made to fit closely against this surface as it is adjusted toward 25 and away from the roll 10. The control of the position of the doctor 120 is facilitated by supporting it upon an arm 126 pivotally mounted at 128 at the center of a plate 130 closing the end of the trough 14. This allows 30 a movement of the doctor 120 along the curved surface 124 without separating it from said surface and by reason of the fact that the center 128 of the trough is eccentric to the center of the roll 10, it permits the doctor 120 to be adjusted toward and away from the roll 10 with great exactness. The outer end of the arm 126 is slotted and a thumb screw 132 is provided passing through the slot in said arm and threaded into the trough 14 by 35 means of which said arm and the doctor carried thereby may be held in adjusted position. This mechanism, as just described, is thus not only efficient in giving an exact determination of the quantity of cement carried up by the roll but, in addition, is exceptionally compact

and out of the way of the operator and will not interfere with the handling of such work as closed vamps. At the same time it is so constructed that it may readily be removed for cleaning when so desired. It will be observed that the trough 14 is provided with an elevated portion 134 at the downgoing side of the roll 10 adjacent to the opening in said trough in order more effectively to prevent the overflow of unused cement which should be carried back into the trough.

70 The presentation of work provided with a flat French binding strip as illustrated in part of Fig. 6 is greatly facilitated by the construction and arrangement of a work-guiding member 140. It will be understood that such work comprises a piece of material such as a leather shoe part 142 to which there has been attached a narrow strip 144, usually of fabric, by means of a row of stitching 146. The work is presented to the cementing machine in the flat condition illustrated at the left in Fig. 6 so that a coating of cement may be applied to either one or both of the opposed surfaces along the edge of the shoe part 142 and the fabric strip 144, it being applied usually to the majority of the width of the fabric strip 144. After the cementing operation has been completed, the strip 144 is folded over the edge of the shoe part 142 into the position illustrated at the right in Fig. 6 to make a so-called French edge, it being understood that the surface 148 of the shoe part is the grain or exposed surface of the leather. It will be evident, therefore, that it is desirable to maintain the strip 144 in flattened condition as it is presented to the rolls 10 and 12 of the machine, and to this end the edge guide 140 is forked to provide an upper arm 150 and a lower arm 152. The upper arm is curved upwardly and terminates in a hook-shaped portion 154 (Fig. 3) providing a flared entrance to facilitate the introduction of work in proper position through the guide 140 and prevent its insertion between the guide and the upper roll 12. In addition, the lower arm 152 is provided with a depending apron-like portion 156 over which the edge of the work is dragged, it being understood that the arrangement is such that this apron-like portion 156 fits snugly against the upper surface of the doctor 120 so that there is no opportunity for the accidental insertion of the work beneath the guide 140. As will be seen from Fig. 5, the upper arm 150 of the guide 140 is so shaped in section that its forward edge (on the right as viewed in Fig. 5) rubs down the fabric strip 144 as it is pulled through the guide so that said strip is smoothed out prior to its presentation to the cement-applying roll 12. In addition, the relative disposition of the arms 150 and 152 is such that the work cannot possibly be fed in a horizontal plane through the guide and the rolls without touching the upper fork arm 80 85 90 95 100 105 110 115 120 125 130

150. Instead, the work is kinked by the guide so that the forward edge of the upper arm rubs against and smooths out the fabric without allowing it to become folded longitudinally. The guide 140 is adjustably held in position by a bolt 158 upon a bracket 160 which is also adjustably held in position upon the trough 14 by means of a bolt 162. This provides for the correct positioning of the 10 edge guide in accordance with the width of the strip 144 and the width of the band of cement which it is desired to apply to said strip. In addition to the edge guide 140 the machine is provided with an edge gage 164 15 (Fig. 2) integral with the bracket 160 and hence adjustably positioned in the machine beside the point of contact between the rolls and arranged to co-operate with the guide 140 in the correct positioning of the work as it 20 passes through the machine.

Having thus described the invention, what I claim as new and desire to secure by Letters Patent of the United States is:

1. In a cementing machine, a work-supporting roll, a cement-applying roll superposed over the work-supporting roll, common means for driving said rolls, a bracket for supporting said cement-applying roll pivotally supported adjacent to the driving connection between said rolls, resilient means separating said rolls, a treadle-operated lever bearing upon an intermediate point in said bracket, and resilient means interposed between said lever and said bracket allowing 35 a slight separation of said rolls independent of the pressure of the treadle operated lever. 2. In a cementing machine, a frame, co-operating rolls mounted upon substantially parallel driven shafts, one of said rolls being 40 arranged to apply cement to a piece of work passing between the rolls, a shaft-supporting bracket for the upper roll pivotally attached to said frame at a point remote from the rolls, resilient means tending to separate said rolls, 45 and an operator-controlled lever bearing against said bracket arranged to press said upper roll into engagement with a piece of work positioned between the rolls.

3. In a cementing machine, a frame, co-operating rolls mounted upon substantially parallel shafts, one of said rolls being arranged to apply cement to a piece of work passing between the rolls, a shaft-supporting bracket for the upper roll pivotally attached to said frame at a point remote from the rolls, resilient means tending to separate said rolls, an operator-controlled lever bearing against said bracket arranged to press said upper roll into engagement with an interposed piece 60 of work, and resilient means interposed between said operator-controlled device and the bracket carrying said upper roll.

4. In a cementing machine, a frame, co-operating superposed rolls carried upon substantially parallel shafts, one of said rolls

being arranged to apply cement to an interposed piece of work, driving connections between said shafts, said upper shaft being mounted in a bracket pivoted to the frame of said machine at a point remote from the 70 rolls, upstanding arms furnishing a guideway for said bracket arranged to prevent lateral deflection thereof, and an operator-controlled lever pivotally mounted in said arms and arranged to engage said bracket 75 to bring said rolls into engagement with a piece of work interposed therebetween.

5. In a cementing machine, a frame comprising a base having an outstretched arm, a roll mounted on a shaft extending through said arm, a co-operating roll mounted upon a substantially parallel shaft carried in a bracket pivoted to the frame of said machine at a point remote from the rolls, one of said rolls being arranged to apply cement to the work, driving connections between said rolls, resilient means tending to separate said rolls, upstanding bracket fingers on said outstretched arm constructed and arranged to guide the up-and-down movements of said shaft-carrying bracket and to prevent lateral deflection thereof, and an operator-controlled lever pivotally mounted in said bracket fingers extending away from the rolls toward the pivot of the shaft-carrying bracket, said lever being arranged for engagement with said shaft-carrying bracket at an intermediate point thereof so that the rolls may be pressed together for engagement with an interposed piece of work. 100

6. In a cementing machine, a frame comprising a base having an outstretched arm, a roll mounted on a shaft extending through said arm, a co-operating roll mounted upon a substantially parallel shaft carried in a bracket pivoted to the frame of said machine at a point remote from the rolls, one of said rolls being arranged to apply cement to the work, driving connections between said rolls, resilient means tending to separate said rolls, upstanding bracket fingers on said outstretched arm constructed and arranged to guide the up-and-down movements of said shaft-carrying bracket to prevent lateral deflection thereof, an operator-controlled lever pivotally mounted in said bracket fingers extending away from the rolls toward the pivot of the shaft-carrying bracket, said lever being arranged for engagement with said shaft-carrying bracket at an intermediate point thereof so that the rolls may be pressed together for engagement with an interposed piece of work, and resilient means interposed between said lever and said shaft-carrying bracket allowing a slight separation of the rolls upon the passage of a thickened portion of the work. 110

7. In a cementing machine, a cement-carrying trough having an opening at its upper side, a cement-applying roll journaled in said 130

trough arranged to project through said opening, and a doctor arranged for co-operation with the upgoing side of the roll adjustably mounted for pivotal movement about an axis disposed opposite to the end of the roll and eccentric to the axis of the roll.

8. In a cementing machine, a cement trough having an opening at the top, a cement-applying roll journaled in said trough arranged to project through said opening, a portion of said trough adjacent to the upgoing side of the roll having a curved external contour, a doctor comprising a curved plate closely fitting and overlying the curved portion of the trough and having an edge portion arranged to co-operate with the roll to determine the amount of cement raised from the trough, and means for adjustably determining the position of said doctor.

15 9. In a cementing machine, a cement trough having an opening at the top, a cement-applying roll journaled in said trough and arranged to project through said opening, the portion of said trough adjacent to the up-going side of the roll having a curved contour, and a doctor the rear edge of which coacts with the up-going side of the roll to control the quantity of cement delivered by the roll, said doctor comprising a plate the lower surface of which is curved to hug the trough and the upper surface of which is curved to avoid interference with the work, said doctor being adjustably mounted on the trough for movement in close relation to the trough as its position is changed to vary the relation of the edge portion of the doctor to the up-going side of the roll.

20 10. In a cementing machine, a barrel-shaped trough having an opening adjacent to its outer end, a cement-applying roll journaled in said trough projecting through the opening thereof, and a doctor comprising a curved plate mounted upon the outer end of a pivoted arm and arranged to co-operate with the upgoing side of said roll to determine the amount of cement lifted out of the trough, said arm being pivotally attached to the trough substantially at the axis thereof.

25 11. In a cementing machine, cooperating rolls one of which is arranged to apply cement to pieces of work, and a work guide mounted adjacent to the intake of said rolls, said guide comprising a fork-shaped member provided with a depending apron attached to the lower side of the fork-shaped member.

30 12. In a cementing machine, co-operating rolls one of which is arranged to apply cement to pieces of work, and a work guide adjustably mounted adjacent to the intake of said rolls comprising a forked member having a hook-shaped finger on one portion of said said forked member overlapping the end of one roll to prevent the insertion of work laterally between said guide and said roll.

35 13. In a cementing machine, co-operating

rolls one of which is arranged to apply cement to pieces of work, and a work guide adjustably mounted adjacent to the intake of said rolls comprising a forked member the upper arm of which has a depending forward edge arranged to bear against a substantial portion of the margin of the upper surface of the work to smooth it out.

40 14. In a cementing machine, co-operating rolls one of which is arranged to apply cement to pieces of work passing therebetween, an edge gage adjustably mounted beside the meeting point of the rolls, and a work guide adjustably mounted adjacent to the intake of the rolls, said work guide comprising a fork-shaped member having a pair of arms, said arms being positioned in staggered relation to each other and to the bite of the rolls to enable said arms to contact with the work to straighten the work as it passes to the rolls.

45 15. In a cementing machine, co-operating superposed rolls one of which is arranged to apply cement to pieces of work passing therebetween, an edge gage adjustably mounted beside said rolls substantially at the meeting point of the rolls, and a co-operating fork-shaped work guide having an upper and a lower arm and adjustably mounted adjacent to the intake of the rolls having a depending apron attached to the lower arm of the fork-shaped member.

50 16. In a cementing machine, a frame, a cement trough having an opening at the top, a cement-applying roll journaled in said trough and arranged to project through said opening, a portion of said trough adjacent to the up-going side of the roll having an arcuate contour, and a doctor the rear edge of which coacts with the up-going side of the roll to control the quantity of cement delivered by the roll, said doctor comprising a curved plate the under side of which fits the arcuate contour of said portion of the trough, said doctor being adjustably mounted so that it may slide over the trough to vary the relation of the edge portion of the doctor to the roll without being separated from the trough.

55 17. In a cementing machine, a frame, a cement trough having an opening at the top, a cement-applying roll journaled in said trough and arranged to project through said opening, a portion of said trough adjacent to the up-going side of the roll having an arcuate contour, an adjustable doctor coacting with said roll, said doctor comprising a curved plate the under side of which fits the arcuate contour of said portion of the trough, said doctor being mounted for adjustment in close relation to the trough to vary the relation of the rear edge of the doctor to the up-going side of the roll and an arm extending across the end face of said trough for supporting and adjustably determining the posi-

tion of said doctor without interfering with the progress of work being dragged over the surface of the doctor.

18. In a cementing machine, a barrel-shaped trough having an opening at its top, a cement roll dipping in said trough and rotatable about an axis eccentric to the axis of the trough with its upper surface projecting above the top of the trough, and a doctor arranged for cooperation with the up-going side of the roll thereby to control the quantity of cement carried by the roll, said doctor being pivotally mounted for adjustment about an axis substantially coincident with the axis of said trough.

19. In a cementing machine, a frame, an outwardly extending barrel-shaped cement trough having an opening at its upper side and closed at its outer end, a cement-applying roll journaled in said trough adjacent to said closed end and rotatable about an axis eccentric to the axis of the trough to project through said opening, and a doctor mounted on an arm pivotally attached to the closed end of the trough near its center thereby to provide for adjustment of the doctor toward and away from the up-going side of the roll to control the amount of cement delivered by the roll.

20. In a cementing machine, cooperating rolls one of which is arranged to apply cement to pieces of work, and a work guide adjustably mounted adjacent to the intake of said rolls and comprising a member having a hook-shaped finger overlapping the end of one roll to prevent the insertion of work laterally between said guide and said roll.

In testimony whereof I have signed my name to this specification.

JOHN W. COSGROVE.
